UNITED STATES PATENT OFFICE.

JOHN M. FEDDERS, OF BUFFALO, NEW YORK, ASSIGNEE TO FEDDERS MANUFACTURING COMPANY, INC., OF BUFFALO, NEW YORK, A CORPORATION OF NEW YORK.

RADIATOR.

1,294,435.

Specification of Letters Patent. Patented Feb. 18, 1919.

Application filed September 12, 1917. Serial No. 191,027.

To all whom it may concern:

Be it known that I, JOHN M. FEDDERS, a citizen of the United States, residing at Buffalo, in the county of Erie and State 5 of New York, have invented new and useful Improvements in Radiators, of which the following is a specification.

This invention relates to a radiator which is more particularly designed for cooling 10 the water of a gas engine and has for its object the production of such a radiator which is simple and inexpensive in construction, efficient in operation and exceedingly strong so that the same is capable of with- 15 standing any unusual strains to which the same may be subjected while in use.

In the accompanying drawings: Figure 1 is a front elevation, partly in section, of the radiator embodying my invention. Fig. 20 2 is a horizontal section taken on line 2—2 Fig. 1. Fig. 3 is a fragmentary vertical section taken on the correspondingly numbered line in Fig. 2. Fig. 4 is a fragmentary perspective view of one of the radiating 25 members of the core containing my improvements. Fig. 5 is a plan view of part of a blank from which the radiating member is constructed. Figs. 6 and 7 are fragmentary perspective views of the water tube 30 walls.

Similar characters of reference refer to like parts in the several figures.

In its general construction my improved radiator comprises a plurality of upright 35 water tubes or passages 1 which are arranged side by side and are of tortuous or zig-zagged form, and a plurality of horizontal air passages 4, arranged between the several water tubes or passages. In the complete 40 radiator the upper and lower ends of the water tubes are connected with the conduits or boxes forming part of the circulating system of the gas engine so that the hot water from the engine as it passes through 45 these water tubes is cooled by the currents of air passing horizontally through the air passages.

Each of the water tubes is constructed of two outer walls or strips 5 of sheet metal, 50 each of which is bent or corrugated into zig-zagged form for producing a succession of summits and valleys on each side of the strip which summits and valleys alternate with each other. Each of these water tube 55 walls or strips is provided with off-sets 6

at its opposite edges and on one side of this wall and on the turns 7 of alternating corrugations thereof which off-sets project laterally from the concave sides of the respective corrugations. The turns of the remaining 60 corrugations are not provided with off-sets but are continuous from edge to edge of this tube strip or wall, thereby forming straight or continuous valleys or bottoms 8 on the opposite side of this strip. The two 65 walls of each group are assembled so that they are parallel and engage each other at their opposite edges, thereby forming a water passage 1 between the same. When thus assembled the convex sides of the continuous turns of the corrugations of one 70 wall engage the concave sides of the off-sets of the turns of the other companion wall, thereby forming closed joints between the walls at their opposite edges and leaving 75 a space between the central parts of these walls which constitute the water passage.

The plurality of air passages 2 arranged between two water tubes are formed, partly by the two opposing walls of these tubes 80 and partly by a radiating member arranged between these two tube walls. In its preferred form this radiating member comprises a plurality of parallel transverse plates 9 arranged in longitudinal rows between the opposing walls of two tubes and each of these plates engaging its opposite edges with the continuous bottoms 8 of the corresponding corrugations in the opposing sides of said walls, a plurality of longitudinal plates 10 arranged lengthwise in a row between said walls and alternating with said transverse plates, and a plurality of coupling straps 11 which are arranged parallel with said transverse plates and each of 85 which is connected at its inner side edge with one of the side edges of the adjacent longitudinal plate, while its outer side edge is connected with the side edge of one of the adjacent transverse plates. In the preferred form each of these straps engages flatwise with the adjacent transverse plate 90 and forms a plait therewith. In the preferred construction a plurality of such straps have their inner edges connected with opposite side edges of one of the longitudinal plates, while the outer edges of these straps 95 are connected with the diagonally opposite outer or side edges of the adjacent transverse plates. The transverse and longitudi- 100 105 110

nal plates of each radiating member are of the same width as the walls of the water tubes and the front and rear ends or edges of the same are flush. The coupling straps 5 are however, of less width than said plates and are arranged at a distance from the ends or end edges of said plates, thereby causing the radiating members to present the appearance of single lines both length- 10 wise and crosswise at the front and rear side of the radiator core. The transverse plates of the radiating members are provided with openings 12 which are preferably formed on the central parts thereof, 15 which serves to reduce the weight of the same and also to provide inter-communication between adjacent air tubes so as to permit a free circulation of air both vertically and horizontally through the air tubes or 20 passages.

Each of the radiating members is preferably constructed from a sheet of metal which is first stamped out in the form of a blank as shown in Fig. 5 and then bent 25 or folded into the form shown in Figs. 1, 3 and 4.

The two water tube walls on opposite sides of each radiating member are preferably connected with each other at the 30 upper and lower ends of the companion radiating member and those two walls are preferably formed from a single strip of sheet metal which may be doubled or folded upon itself midway of its length and 35 at the end of the companion radiating member, as shown at 13 in Fig. 1, while the opposite ends of this strip forming these two tube walls may be interlocked with each other by means of a lock seam or similar 40 joint, as shown at 14 in the same figure.

A radiator unit is thus formed in which the two opposing walls of adjacent water tubes form the outer members, while the radiating element between the same forms 45 the intermediate member. In the manufacture of the radiator a plurality of such units are assembled side by side so that the outer walls of each unit interlock with the water tube walls of adjacent units after 50 which the core thus formed by the plurality of units is dipped in solder so as to permanently connect the front and rear edges of each pair of water tube walls and render the same water tight or leak proof and at 55 the same time cause the solder to unite the radiating members with the water tube walls so as to hold the same firmly against displacement relatively to each other.

Inasmuch as the lateral edges of the 60 transverse plates and coupling straps engage with the bottoms of the continuous turns of the corrugations of the water tube walls, these parts are accurately, easily and reliably centered relatively to each other, 65 and owing to the increased soldering sur-

face which is by this means obtained between the lateral or side edges of these transverse plates and coupling straps and the continuous bottoms of the corrugations of the water tube walls, a much stronger 70 and durable connection is obtained between the same which increases the rigidity of the radiator core and enables the same to withstand more effectively the shocks or strains to which the same is liable to be 75 subjected while in use.

In practice the outer walls of the radiator tubes are constructed of copper or of brass or similar metal which is not liable to corrode by reason of the action of the water 80 which passes through the same and thus renders the radiator water tight. The radiating members may, however, be constructed of terne or other inferior metal which is of lower cost than the water tube 85 walls inasmuch as the same is not exposed to the corroding action of water, but still possesses sufficient heat conducting capacity to efficiently carry off the heat from the water tube walls to the adjacent atmosphere. 90 The radiator core can therefore by this means be produced at much less cost and still provide sufficient radiating capacity for all practical purposes.

I claim as my invention:

1. A radiator unit comprising two outer corrugated walls each of which is of zig-zag form, and an intermediate radiating member arranged between said outer walls and comprising a plurality of transverse plates 100 arranged in a longitudinal row between said outer wall and each engaging its opposite side edges with the bottoms of the corresponding corrugations on the opposing sides of said outer walls, a plurality of longitudinal plates arranged between said outer walls and alternating with said transverse plates, and a plurality of coupling straps connecting opposite side edges of each longitudinal plate with the side edges of the adjacent 110 transverse plates.

2. A radiator unit comprising two outer corrugated walls each of which is of zig-zag form, and an intermediate radiating member arranged between said outer walls and comprising a plurality of transverse plates arranged in a longitudinal row between said outer walls and each engaging its opposite side edges with the bottoms of the corresponding corrugations on the opposing sides of said outer walls, a plurality of longitudinal plates arranged between said outer walls and alternating with said transverse plates, and a plurality of connecting straps, a pair of which have their inner edges connected with opposite side edges of one of the longitudinal plates while their outer edges are connected with the diagonally opposite side edges of the adjacent 120 transverse plates.

3. A radiator unit comprising two outer corrugated walls each of which is of zig-zag form, and an intermediate radiating member arranged between said outer walls and comprising a plurality of transverse plates arranged in a longitudinal row between said outer walls and each engaging its opposite side edges with the bottoms of corresponding corrugations on the opposing sides of said outer walls, a plurality of longitudinal plates arranged between said outer walls and alternating with said transverse plates, and a plurality of coupling straps which are arranged parallel with said transverse plates, and one of which connects one side edge of a longitudinal plate with one side edge of the adjacent transverse plate while another one connects the opposite side edge of the respective longitudinal plate with the diagonally opposite side edge of another transverse plate. 10
4. A radiator unit comprising two outer corrugated walls, each of which is of zig-zag form, and an intermediate radiating member arranged between said outer walls and comprising a plurality of transverse plates arranged in a longitudinal row between said outer walls and each engaging its opposite side edges with the bottoms of the corresponding corrugations on the opposing sides of said outer walls, a plurality of longitudinal plates arranged between said outer walls and alternating with said transverse plates, and a plurality of coupling straps one of which connects one side edge of a longitudinal plate with one side edge of an adjacent transverse plate while another one connects the opposite side edge of the respective longitudinal plate with the diagonally opposite side edge of another transverse plate, said plates being of the same width and said straps being of less width than said plates. 15
5. A radiator unit comprising two outer corrugated walls each of which is of zig-zag form, and an intermediate radiating member arranged between said outer walls and comprising a plurality of transverse plates arranged in a longitudinal row between said outer walls and each engaging its opposite side edges with the bottoms of the corresponding corrugations on the opposing sides of said outer walls, a plurality of longitudinal plates arranged between said outer walls and alternating with said transverse plates, and a plurality of coupling straps one of which connects one side edge of a longitudinal plate with one side edge of an adjacent transverse plate while another one connects the opposite side edge of the respective longitudinal plate with the diagonally opposite side edge of another transverse plate, said plates being of the same width and said straps being of less width than said plates. 20
